UNITED STATES PATENT OFFICE

ALFRED M. MARTIN, OF CHICAGO, ILLINOIS

LATCH MEANS FOR BINDERS

Application filed November 3, 1928. Serial No. 816,897.

This invention relates to latching means for book-type binders of the kind in which there is a pair of prong-carrying back members movable toward and away from each other, ordinarily on a hinge connection.

The general object of the invention is to provide a latch or catch device for such binders which may readily be rendered inoperative whereby the backs may be moved 10 toward or away from each other throughout a wide range, while being susceptible of being held in the fully-closed or in partly-open position at the will of the operator.

It is not new to provide means for holding 15 the back members in the closed and in a partly-open position. In such prior devices it becomes necessary to release the catch manually as an almost constant operation in certain uses of the book. By rendering the 20 latching mechanism inoperative much if not practically all of this labor is avoided. A feature of the present invention is that the desired results are obtained with a single manual control.

25 In my copending application, Serial Number 313,397, filed October 19, 1928, I have shown and claimed means for accomplishing this result in connection with a certain mechanism described and claimed in a copending application of Harry J. Dornes, 30 Serial Number 287,128, filed June 21, 1928. The present invention is directed to the utilization of a single latching mechanism as distinguished from the use of an auxiliary 35 latching device, for example such as is shown by the two copending applications mentioned. In this regard further, the present invention employs largely what is old and well-known and calls for little additional expense over 40 the use of the ordinary latch mechanism for holding the book closed.

The chief object of the invention in practice is to permit the operator readily to remove and insert sheets where the amount 45 thereof is considerable and the book must be partly closed to swing sheets from one side to the other. This may be a substantially continuous operation all day long, as where the sheets are being removed, written upon 50 by machine and then replaced. According

to this invention and that of my said copending application this may be without having to operate the releasing mechanism. It effects a great saving in time and labor.

The specific object of the present invention is to provide simple and low-cost means for accomplishing the general results, more particularly in connection with the so-called "non-shift" binder, namely the kind which is not in accordance with my Patent No. 1,269,479 of June 11, 1918.

In the drawings Figure 1 is an end view of the preferred or hinged type of binder in a partly open and unlocked position, embodying the present invention, the lids or covers being broken away; Fig. 2 is a fragmentary top view of the binder fully closed, the lids or covers being shown in section; Fig. 3 is a fragmentary top view showing the binder partly open and locked; Fig. 4 is a fragmentary top view showing the binder with its parts in the relative position of Fig. 1; Fig. 5 is a bottom partly-sectional view, with the binder closed, showing the latching and releasing mechanism; Fig. 6 is a fragmentary section, as on the line 6-6 of Fig. 5, showing the parts of Fig. 5 in the same relative positions and in side elevation in inverted position with the sheet-holding prongs omitted; and Fig. 7 is a view like Fig. 6 but so showing the parts in another relative position.

Binders of the kind referred to are invariably provided with latch or catch means for holding the back members releasably closed. 85 Usually there is such a catch at each end, but it is not necessary to show both since they are alike and simultaneously operated. These usual and well-known locking means are shown here as comprising a headed curved 90 leaf-like latch projection 10 rigidly secured to back member A and projecting so as to enter the opening 11 in the inner wall 12 of back member B. Mounted for sliding movement in the hollow interior of back member B, and 95 in the corner between the walls 12 and 15 thereof, is an angle-iron piece denominated as a whole 13 and which comprises a web 13^a lying against the wall 12 and a web 13^b resting upon the wall 15 of the frame, a re- 100

taining bracket 14 extending over the web 13^b and secured as by spot-welding to the longitudinally-extending sheet metal frame part or wall 15.

5 The web 13^a has an opening or gateway in it at 9 (Figs. 6 and 7) whereby the latch projection 10 may pass through the opening 11, which would otherwise be closed by the web 13^a, and there is thus provided a part 10^a of the web 13^a adjacent to the inner end of the opening 11 and adapted to be engaged by either of the catch elements 10^a or 10^b of the latch projection 10. When the part 13^a is engaged by the catch element 10^a as in Figs. 5 and 6 the back elements are held in the fully closed position, and when engaged by the catch element 10^b the backs are held in the position shown by Fig. 3, namely partly open and with the prongs 16 and 17 sufficiently 20 overlapped to permit sheets to be transferred from one side to the other of the binder.

A tension spring 18 secured to the angle-iron piece 13 and to the bracket 14 draws the angle-iron piece, and therefore the latch-holding part 13^{aa} thereof, toward the lower end of the binder as viewed in Fig. 5, or so as to be engaged by one or the other of the catch elements 10^a and 10^b.

The web 13^b of the angle-iron piece terminates in a bent-up finger piece 22 which extends beyond the metal boxing or frame and is freely available at the end of the book next to the operator when in use.

In this connection it should be mentioned that broadly speaking the construction including the finger-piece, the angle-iron piece 13 having the catch part 13^{aa}, the latch projection 10 with its part 10^a, (omitting 10^b) together with a spring functioning in all material respects like the spring 18, are severally and collectively old and well-known. They have been used heretofore for holding the book fully closed.

Note from Figs. 6 and 7 that on the frame part 15 and adjacent to the finger-piece is a stop 25 consisting of a small rectangular piece of metal spot-welded to the part 15, and also that on the angle-iron web 13^a adjacent to the stop 25 is a similar piece of metal 26, the same being spot-welded to the part 13^a and acting as a catch coacting with the stop 25. The part 13^a adjacent to the finger piece is springy and tends to force the finger-piece downward as viewed in Fig. 6. To aid this springiness I provide a slot 27, Fig. 5, in the part 13^a, this feature being also shown in my said co-pending application.

If the finger-piece in Fig. 6 were pushed or advanced inward against the pull of spring 18 the catch 26 would first slide past and then become caught by the stop 25, as shown in Fig. 7, and the latch-holding part 13^{aa} would similarly be advanced to its position in Fig. 7, clearing the hole 11 and the path of movement of the catch projection 10^a. The binder

may now (Fig. 7) be fully opened and closed, just as though the holding part 13^{aa} were not present. In the past it was possible to release the catch element 10^a by pushing the finger-piece inward, but in the past the holding part as 13^{aa} was not held or maintained in that advanced position, but, on the contrary, as soon as the operator's finger or thumb was removed the finger-piece and associated parts moved outward again into position to be again caught on moving the backs together.

The catch element 10^b does not extend inward, or to the left as viewed in Figs. 6 and 7, as far as does the catch element 10^a. In other words, the effective portions of these catch elements are on transverse lines spaced substantially apart, and these catch elements are arranged to force the part 13^{aa} successively farther inward when the book is closed from its fully-open position. This arrangement is not, however, necessary, and both catch elements could be on the same transverse lines.

Fig. 6 shows the holding part 13^{aa} at the limit of its movement to the right so as to engage the catch element 10^b when the book is closed from fully open position and that it cannot move outward or to the right any farther because the catch 26 at that time abuts the end wall of the housing. Any suitable stop limiting action may be employed. If the book were open, as in Fig. 1, and the relative position of the holding elements 25 and 26 were as shown by Fig. 6, it is clear that the backs could be moved together somewhat on the hinge connection at 19, or into the position of Fig. 3, when the catch element 10^b would become caught by the holding part 13^{aa}.

This position of Fig. 3, wherein the backs are held in a partly-open position, is an exceedingly advantageous one in some operations wherein it is desired to move sheets transversely from one set of prongs to the other, back and forth, as for making entries as by pen and ink upon the sheets while they remain in the binder. In some offices where the binder is used this operation may take place all day long.

From time to time, however, during such operations, sheets are removed and others inserted, and in such instances it is necessary to open the book further. According to these improvements the finger-piece may, to that end, be pushed inward slightly, not the full distance, but merely enough to release the catch element 10^b, allowing the finger-piece then to come back to its position in Fig. 6 with the parts 25 and 26 still overlapped. Thereupon when it is desired to close the book partly again as in Fig. 3 it is only necessary to move the backs together till the relatively short projection 10^b (calling it short

in the sense of not being so far advanced inwardly) becomes caught.

With the parts 25 and 26 in the relative position of Fig. 6 the backs may be completely closed, in which case the catch projection 10^a comes into effect; but in such case the parts 25 and 26 still remain overlapped, and as soon as the book snaps shut the parts 25 and 26 again resume their relative positions shown by Fig. 6. This is owing to the fact that the full clearance at 30, Fig. 7, between the catch element 10^a and the holding part 13^{aa} is not required when the backs are simply pushed together. There is an excess 15 of clearance there. The dotted line position of the part 26 in Fig. 7, still overlapping, though but slightly, the part 25, is the position of part 26 when the backs are simply pushed together. In order to catch the parts 20 25 and 26 together the finger-piece must be pushed inward enough to provide the excess clearance at 30.

Through the coaction of the parts 25 and 26 the binder-latching mechanism is held releasesably inoperative in the full-line relative positions of Fig. 7. All that is necessary to release the latching mechanism from the position of Fig. 7 is to push upward in that figure the finger-piece 22 sufficiently to cause 25 the holding element 26 to slide over and upon the stop 25. In Fig. 1 the releasing movement consists merely in pushing or striking downward with the finger upon the finger-piece 22, the spring 18 then moving the associated elements outward.

Should it be desirable to render inoperative merely the latching mechanism with respect to the catch element 10^b it is clear that that may be accomplished by merely proportioning these stop elements 25 and 26 so that when these parts are functioning as in Fig. 7 the part 13^{aa} is held advanced only far enough to engage the catch element 10^b.

The latch projection denominated as a whole 10 is shown as being carried rigidly by one of the back members. In some constructions a corresponding element is carried by a movable member terminating in the finger-piece so that the latch projection is moved inward and outward. It is immaterial to the present invention whether the latching projection or its coacting holding member is the one movable by the finger piece. The latching projection may be variously shaped, and there may be many intermediate positions in which the backs may be held, as by numerous catch elements on the latching projection.

The strip 28, Figs. 5, 6 and 7, is to be understood as leading to a place near the other end of the binder to operate a corresponding latching mechanism at that end.

I contemplate as being included in this invention all such changes, departures and modifications from what is thus specifically

illustrated and described as fall within the scope of the appended claims.

I claim:

1. In a prong binder, a pair of back members relatively mounted so that at least portions of the same move toward and away from each other and means for holding the back members closed and also in partly-open position, said holding means comprising a latching projection carried by one of the back members and interengaging means carried by the other thereof, said latching projection having catch elements for holding the binder closed and also in a partly-open position, with manually-controlled means for releasing said holding means whereby the binder may be fully opened, in combination with means for releasably maintaining said holding means inoperative. 70 75

2. The combination of claim 1 hereof in which said back members are hinged together. 80

3. The combination of claim 1 hereof in which said last-mentioned means and said means for releasing said holding means are under the control of a common finger-piece. 90

4. In a binder of the character described, a pair of back members hinged together, in combination with a unitary latch-and-catch device for holding the back members releasably in a partly-open position, and means for releasably maintaining said holding means inoperative. 95

5. In a binder of the character described, a pair of back members hinged together, in combination with a unitary latch-and-catch device including a member having a plurality of notch-like formations therein for holding the back members releasably in a partly-open position and also in closed position, and means for releasably maintaining said holding means inoperative. 100 105

6. In a binder of the character described, a pair of back members hinged together, in combination with a unitary latch-and-catch device for holding the back members releasably in a partly-open position, means including a finger-piece adjacent to one end of the binder for releasing said holding means, and means under the control of said finger-piece for releasably maintaining said holding means inoperative. 110 115

7. In a binder of the character described, a pair of back members hinged together, in combination with a latch-and-catch device for holding the back members releasably closed, and means for releasably maintaining said holding means inoperative. 120

8. In a binder of the character described, a pair of back members hinged together, in combination with a locking projection rigidly secured to one back member and having a plurality of tooth-like elements thereon, cooperating means carried by the other back member and mounted for relative movement 125 130

to engage and release said tooth-like elements, for holding the back members in various relative positions with respect to each other, a finger-piece for moving said cooperating member, and means under the control of said finger-piece for releasably maintaining said cooperating member free of one of said tooth-like elements adapted to hold the backs in a partly-open position.
